UNITED STATES PATENT OFFICE.

HENRY B. SOMMER, OF PHILADELPHIA, PENNSYLVANIA.

DESIGN FOR AN EXHIBITING-STAND.

SPECIFICATION forming part of Design No. 15,480, dated October 21, 1884.

Application filed August 4, 1884. Term of patent 3½ years.

To all whom it may concern:

Be it known that I, HENRY B. SOMMER, a citizen of the United States, and a resident of Philadelphia, Pennsylvania, have invented or 5 produced a new and original Design for an Exhibiting-Stand, of which the following is a specification.

My design for an exhibiting-stand is fully shown in the accompanying drawing.

10 The design comprises the representation of a block-letter having a central filling or cushion and an outlining-border, a, contrasting strongly therewith.

15 The letter R is shown in the drawing; but the design includes any letter.

I claim—

The design for an exhibiting-stand, said design consisting of the representation of a block-letter with central filling or cushion and outlining-border contrasting therewith, as shown 20 and described.

In testimony whereof I have signed my name to this specification in the presence of two subscribing witnesses.

H. B. SOMMER.
